UNITED STATES PATENT OFFICE.

MARCEL VIARD, OF BARON, FRANCE.

MEDICAL APPARATUS FOR HOT-AIR SUPPLY.

Application filed April 25, 1922. Serial No. 556,395.

To all whom it may concern:

Be it known that I, MARCEL VIARD, citizen of the French Republic, residing at Baron, Oise, France, have invented certain new and useful Improvements in Medical Apparatus for Hot-Air Supply, of which the following is a specification, reference being had therein to the accompanying drawing.

10 My invention relates to medical apparatus for hot air supply which are used in the treatment of certain affections such as rheumatism.

Known types of medical apparatus for delivering hot air are in use which are constituted for example of an air fan causing a current of air to pass over a source of heat such as an alcohol lamp. But apparatus of this kind are attended with a number of 20 drawbacks; among others, the air is supplied at a comparatively low temperature; it is necessary to rotate the air fan by hand, and this will occupy one hand of the operator who is already required to hold the device in the other hand, or in other cases the air fan is mechanically operated, thus requiring for example, the use of electric current. Apparatus is also employed wherein the air is given a high temperature by 25 making use of the electric current for heating resistances through which the air current is delivered, but such devices require an electric contact device to be located in immediate proximity, and hence are not available 30 for general use, and especially in outlying districts.

This invention relates to a portable apparatus which is adapted to produce very high temperatures and possesses few mechanical parts; it does not depend upon the use of electric current as the source of heat nor as a source of power for air-blowing purposes; it is of convenient use in all situations and may be set in operation within 40 a very short time, and has no fragile parts nor is it subject to breakdown for any reason; it has as very reliable working, and the operator will always have one hand free in case he should be obliged to hold the apparatus, and he may even have both hands free where the device is placed upon a table.

The invention is characterized by the combination of an apparatus adapted to burn combustible vapor emitted under pressure by a liquid which is vaporized by heat, for example, a soldering lamp of a known commer-

cial type, having a chimney which can be removably mounted upon the blowing tube in order to receive the gases of combustion, the said chimney being provided in the interior and for part of the length with a metal tube for the insufflation of air, which is preferably in coaxial position, so as to be brought to a very high temperature by the gases of combustion surrounding the same and to 60 transmit upon the entire periphery a considerable amount of heat to the air which is delivered into it; this air will consequently be heated to a very high temperature, and 65 passes out through the end of the chimney, 70 becoming mixed with the gases of combustion. The insufflation of the air can be obtained by any suitable means, but since the soldering lamp is adapted to operate on a small supply of air in proportion to the total 75 mass of gases of combustion proceeding from the lamp, the invention relates more particularly to a device for air blowing by the mouth having few mechanical parts. The heated air is forced through the chimney 80 preferably by the use of a flexible tube having a mouthpiece at one end and connected at the other end with the tube extending within the chimney.

The following description, together with 85 the accompanying drawings which are given by way of example, sets forth an embodiment of the invention.

Fig. 1 shows a soldering lamp of known 90 type, and the various elements which are to be added thereto in order to constitute a medical apparatus for hot air supply. Fig. 2 is an external view of the complete apparatus.

L is a soldering lamp of commercial type 95 having the main body 1, blowing tube 2, gasoline needle valve 3, heating vessel for starting purposes 4, and folding base 5.

According to the invention, I provide a 100 sheet of metal chimney C of greater or less length whereof the rear part 6 which is preferably perforated and has for example a flaring end, can be mounted for instance by means of the jaw G upon the blowing tube 2, of the lamp so that the air is allowed 105 to pass freely between the tube 2 and the chimney. In this case the jaw G is provided with a sleeve 7 which is slidable on the tube 2 and comes into contact with the shoulder 8. The said sleeve is integral with the jaws 9 engaging the perforated rear part 6 of the chimney C. An insufflation tube 110 10

which is provided with the nipple 12 for rubber tube connection is caused to enter the chimney C, Fig. 1, and is extended within the latter for a suitable length t , occupying preferably the coaxial position. For centering purposes, the tube t is cut in cross-shape at the end, and the parts 11 are expanded so as to bear upon the end of the wall of the chimney.

10 Fig. 2 shows the apparatus in the operative position, with a rubber hose T fitted upon the nipple 12.

The operation of the said device is as follows:

15 The soldering lamp is filled with gasoline and is caused to operate in the known manner by means of a small amount of alcohol which is ignited in the vessel 4, then opening the needle 3. The flame will pass 20 through the chimney C at a very high temperature and will heat the air supply tube t to redness. The air may enter freely through the rear perforations in the chimney and through the space between the 25 chimney and the sleeve 7, according to the arrow F, and will become mixed with the gases of combustion. The operator blows with the mouth in a moderate manner 30 through the mouthpiece of the tube T; this air is raised to a very high temperature and is discharged from the end of the tube t ; it is mixed with the column of gas of combustion which passes through the chimney and draws in air according to the arrow F, 35 and passes out of the end of the chimney, thereby forming a column of hot air (at about 800° centigrade) having a greater or less length in front of the chimney. Should 40 a local treatment be required, the end of the chimney C may have secured thereto a removable tube of conical shape having a hot air discharge orifice of smaller diameter than the chimney.

The apparatus can be mounted on a table, 45 Fig. 2, and the patient may bring the treated part before the chimney C, and in this case the operator will have both hands free. In all other circumstances, the operator will have one hand free.

50 Claims:

1. A medical apparatus for the supply of hot air comprising in combination, a lamp having a burner adapted to supply a flame by the combustion of the vapors of a combustible liquid, a chimney positioned in front of the burner for receiving the flame therefrom, said chimney having perforations in the rear portion thereof, and means 55 providing an additional air current to force the heated air through the chimney.

2. A medical apparatus for the supply of hot air comprising in combination, a lamp having a burner adapted to supply a flame by the combustion of the vapors of a combustible liquid, a chimney positioned in 60

front of the burner for receiving the flame therefrom, said chimney having perforations in the rear portions thereof, and an insufflation tube extending longitudinally within the chimney serving as a guide to 70 an additional air current for forcing the heated air through the chimney.

3. A medical apparatus for applying hot air to parts of the human body, having in combination a lamp, a chimney, means for 75 securing said chimney to said lamp, and an insufflation tube extending longitudinally within said chimney.

4. A medical apparatus for applying hot air to parts of the human body, having in combination a lamp, a chimney, independent 80 resilient means for securing said chimney to said lamp, and an insufflation tube extending longitudinally within said chimney.

5. A medical apparatus for applying hot air to parts of the human body, having in combination a lamp, a chimney having perforations in one end thereof, resilient means connecting the chimney to said lamp, an insufflation tube extending longitudinally 85 within said chimney and having a portion thereof projecting laterally through and beyond the chimney.

6. A medical apparatus for supplying hot air to parts of the human body, having in combination a lamp, a chimney provided with a flaring end, a spring jaw mounted on said lamp and removably engaging said chimney, said chimney having perforations 90 therein adjacent the flared end, and an insufflation tube having a portion extending longitudinally within the chimney and bent laterally to project from the chimney, and an air supply means connected to the outer portion of the insufflation tube.

7. In combination, a lamp of the class described having a reduced end, a chimney, means for removably securing said chimney to said lamp, and an insufflation tube 100 extending longitudinally within said chimney having at one end a plurality of diverging fingers contacting with the inner wall of said chimney.

8. In combination, a lamp of the class described having a reduced end, a chimney, means for removably securing said chimney to said lamp, an insufflation tube extending longitudinally within said chimney having at one end a plurality of diverging fingers contacting with the inner wall of 110 said chimney, and its opposite end projecting laterally through an opening in the wall of said chimney.

9. A medical apparatus for applying hot air to parts of the human body, having in combination a lamp provided with a reduced neck, a container secured to said lamp adjacent said neck, a chimney having a perforated and flared end, a resilient jaw member mounted on said neck adapted to 120 125 130

movably secure said chimney to said lamp, an insufflation tube extending longitudinally within said chimney, and means for ventilating the interior of said chimney.

- 5 10. In combination, a lamp of the class described having a reduced neck, a container secured exteriorly to said lamp, a perforated chimney having a flared end, means for removably securing said flared end to said

10 neck, a control handle projecting laterally

from said lamp, a tube longitudinally disposed within said chimney, said tube having a plurality of diverging fingers contacting with the inner periphery of said chimney and a portion extending laterally through 15 the wall of said chimney.

In testimony whereof I affix my signature.

MARCEL VIARD.
